UNITED STATES PATENT OFFICE.

BENJAMIN HOLMES, OF NEW YORK, N. Y.

IMPROVEMENT IN BED-BOTTOMS.

Specification forming part of Letters Patent No. 135,989, dated February 18, 1873.

To all whom it may concern:

Be it known that I, BENJAMIN HOLMES, of New York, in the county and State of New York, have invented a new and useful Improvement in Spring Bed-Bottoms, of which the following is a specification:

This invention relates to the construction of spring bed-bottoms; and consists in the mode of arranging and confining the springs, hereinafter described.

In the drawing, Figure 1 represents a top-plan view of my improved spring bed-bottom. Fig. 2 is a vertical longitudinal section of Fig. 1 taken on the line *x x*. Fig. 3 is a vertical cross-section of Fig. 2 taken on the line *y y*.

Similar letters of reference indicate corresponding parts.

A represents the springs, of the kind known as the double conical spring. B is a central frame of slats, corresponding in length and breadth to the size of the bed-bottom, or nearly so, placed in the middle of the bottom, as represented in Figs. 1 and 3. C represents straps of web, leather, or other suitable material, by which the springs are attached to the slats of the frame. D represents the slats. In Fig. 1 these slats are shaded, showing the springs attached to each edge, and it will be observed that each spring has two fastenings, one on each side of the slat. By making the slats of the proper width and arranging the springs upon either side, as seen in the drawing, the requisite number of springs is distributed uniformly, and so that each may bear

its proper proportion of the weight. The springs are held at top and bottom by twine or cord, arranged in the usual manner, with a border band of rattan or wire, E, surrounding the springs and forming the boundary of the bottom. The bottom is incased in strong cloth F, with cotton batting G in the sides.

In the drawing, one side of the bottom is seen finished, and the other unfinished. When the bottom is fully completed, it may be used either side up.

The trouble with spring bed-bottoms has heretofore been in keeping the springs in place. If the twine breaks or wears off the whole set becomes disarranged, and the bottom demands repairs. By securely fastening them to the central frame, as represented, all trouble is avoided, each spring has a secure anchorage, and a spring bed-bottom is produced which is unexcelled for comfort, strength, and durability.

Having thus described my invention, I claim as new and desire to secure by Letters Patent—

1. The arrangement of the springs A in regard to the slats D, substantially as shown and described.
2. The straps or fastenings C, in combination with the spring A and slat D, as and for the purpose described.

BENJAMIN HOLMES.
